DRAIN PLUG AND LATCH THEREFOR

Dan McVey, Bayles, Calif.

Application October 2, 1946, Serial No. 700,649

3 Claims. (Cl. 220—39)

1

This invention relates to an improved drain plug for the crankcase of motor vehicles or other equipment using lubricants that must be changed over a period of time.

An object of the invention is to provide a drain plug that is easy to operate, can be quickly removed and prevents the danger of ruining the threads in the crankcase during the installing or removal of the plug for draining the lubricant therefrom.

With the above and other objects in view, the invention consists of the novel details of construction, arrangement and combination of parts more fully hereinafter described, claimed and illustrated in the accompanying drawing in which:

Figure 1 is a side elevation of an embodiment of the invention;

Figure 2 is the same as Figure 1 turned at an angle of ninety degrees;

Figure 3 is a vertical section on line 3—3 of Figure 1;

Figure 4 is the same on the line 4—4 of Figure 2;

Figure 5 is a transverse section on line 5—5 of Figure 1;

Figure 6 is the same as Figure 5 with the latch in position for removal of the plug;

Figure 7 is a bottom plan view of the device and

Figure 8 is a top plan view thereof.

Referring more in detail to the drawing, the drain plug 10 comprising the invention consists of two parts which are inter-connected to form a complete unit.

Part 11 comprises a sleeve 12 which is externally threaded to be mounted in the flanged opening 13 of the crankcase 14 and an annular lower marginal hex-shaped flange 15 on the lower end thereof engages the flange 13 when part 11 is threaded therein.

Part 16 comprises a sleeve 17 which is loosely mounted in the sleeve 12 so that it can be removed, but not loose enough to permit lubricant to seep between the contacting walls thereof. The sleeve 12 is provided at its lower end with a circular cap 18 which is substantially the same size as the flange 15, and extending beyond the sleeve engages the flange 15 when it is in position, and the face of the cap is provided with a slot 19 for the turning thereof with a screw driver or the like.

The flange 15 is provided with a bore 20 in which is rotatably mounted the straight portion 21 of the key latch 22. The portion 21 engages 55 in the groove 22 in the sleeve 17 to retain the part 16 in part 11, and a cutout 23 in the portion 21 permits removal of the part 16 for the draining of the crankcase. Portion 21 of the latch has the arm 24 extending from one 60

end at right angles thereto, and this arm engages the cut 25 in the flange 15 to retain the latch in latching position, and this arm has a slightly curved end 26 for the unlatching thereof.

The other end of the portion 21 is provided with an arm 27 formed at an angle thereto, and this arm has a second arm 28 bent at right angles thereto to engage the face of the cap 18.

The part 11, when installed in the crankcase, 10 need not be removed since the plug can be separated by movement of the latch to unlock part 16, which is turned half way to permit the cutouts to coact so that part 16 can be pulled out to drain the crankcase.

It is believed that from the foregoing description, the construction and operation of the invention will be apparent to those skilled in the art, and it is to be understood that changes in the minor details of construction, arrangement and combination of parts may be resorted to, provided they fall within the spirit of the invention and the scope of the appended claims.

Having thus described the invention, what is claimed as new and desired to be secured by Letters Patent is:

1. A two part drain plug for crankcases comprising an externally threaded sleeve, having a lower hex-shaped marginal flange, a second sleeve mounted in said first sleeve, a cap on said second sleeve adapted to engage the flange on said first sleeve to provide a leak proof joint and means for latching said second sleeve in said first sleeve in fixed relation thereto.

2. The invention as in claim 1 wherein the means for latching said second sleeve in said first sleeve comprises a spring latch having a straight portion rotatably mounted in the flange on said first sleeve, an arm on said straight portion adapted to engage said flange and a second arm on said straight portion adapted to engage the outer surface of said cap.

3. The invention as in claim 1 wherein said second sleeve is provided with a cutout to receive said latch means, and said latching means is provided with a cutout which when positioned to coincide with said first sleeve will permit removal of the second sleeve from the first sleeve.

DAN MCVEY.
